NONREFILLABLE BOTTLE AND PARTS
THEREOFAbraham Podel, New York, N. Y., assignor to
Anchor Cap & Closure Corporation, Long Is-
land City, N. Y., a corporation of New York

Application June 22, 1935, Serial No. 27,854

10 Claims. (Cl. 215—22)

The present invention relates to containers and more particularly to nonrefillable containers and inserts therefor.

In the sale of intoxicating liquors and various other products, manufacturers advertise their brands and retain the good will of customers by maintaining a high standard of quality for their products. Such manufacturers are particularly anxious that their products reach the consumers in good condition with the original contents of the package. Consumers are even more anxious to get the quality which they request and pay for. During the period of prohibition, unscrupulous persons became very proficient in counterfeiting labels and packages, in adulterating liquors and in substituting inferior brands for good brands of liquors. Manufacturers are still plagued with such practices and particularly with the refilling of bottles. Little ingenuity is required to buy discarded bottles, with or without labels thereon, from second hand bottle dealers, refill the bottles with inferior products, counterfeit the labels if necessary, and sell them as genuine products. Frequently, such persons defraud the government of the taxes due on the liquor, making it objectionable to the bottler, the consumer and the government.

Such practices are so prevalent that every effort has been exerted to prevent them. Numerous attempts have been made to provide nonrefillable bottles and numerous patents have been granted therefor. Such attempts and the structures shown in the patents have not been successful because the bottles could be easily refilled or because the structures were so expensive that the cost was prohibitive. Two or three of the many alleged nonrefillable bottles designed reached the market but were unsuccessful for the reasons noted.

The present invention aims to overcome the above objections by providing a nonrefillable insert which will prevent the refilling of bottles. The invention also aims to simplify such constructions and to reduce their cost so that the price will not prevent their sale and commercial use.

An object of the present invention is to provide a practical nonrefillable bottle and an insert therefor.

Another object of the invention is to provide a simple insert for a bottle which will prevent the refilling thereof.

Another object of the invention is to reduce the cost of a nonrefillable bottle and of the insert therefor.

Another object of the invention is to reduce the number of parts in a nonrefillable bottle and to simplify their construction.

Another object of the invention is to simplify

the construction and assembly of the parts of a nonrefillable bottle.

Another object of the invention is to provide a nonrefillable bottle with a valve member adapted to be automatically operated whenever attempts are made to refill the bottle.

A further object of the invention is to provide a valve member adapted to remain in closed position regardless of the position of the bottle except when the bottle is in substantially inverted position and in that case, if an attempt is made to refill the bottle, the valve member is light enough to float into closed position.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is a sectional view of a preferred embodiment of an insert assembled in the neck of a bottle;

Fig. 2 is a sectional view along the line 2—2 of Fig. 1;

Fig. 3 is an exploded view illustrating the several parts of the insert;

Fig. 4 is a sectional view similar to that shown in Fig. 1, with the bottle tilted to illustrate the operation of the valve and the ball member of the insert, the position of the neck being such that the valve member is about to open, as shown in dotted lines;

Fig. 5 is a detailed view of the projections on the valve chamber adapted to attach the cover thereto; and

Fig. 6 is a sectional view of another form of the invention assembled in the neck of a bottle.

Referring again to the drawings illustrating the preferred embodiment, and more particularly to Figs. 1 to 4 and 6, there are shown the several parts of the device which will be first referred to in a general way and later described specifically. The device preferably comprises a bottle 1, which may be an ordinary bottle or container for intoxicating liquors or other products, and an insert for the bottle to prevent refilling thereof. The insert preferably comprises a casting or valve chamber 2 and a cover or hood 4 adapted to be secured together to confine therein a valve member 5, a weight or ball 6 and a baffle member 7. An annular gasket 8 preferably seats on the rim of the container with its upper side engaged by the chamber member 2 and cover member 4. A suitable band 9, pref-

50

55

55

60

erably a continuous band of metal, is telescoped over the cover member in the upper end of the bottle with its lower edge 10 rolled into permanent engagement with the neck of the bottle, whereby the insert cannot be removed without visible indications thereof.

Referring to the several parts of the invention in more detail, the casing or chamber member 2 is preferably in the form of a substantially cylindrical or tubular member with the lower part 11 thereof reduced in size and having an aperture 12 in the lower end thereof. A valve seat 14, preferably slightly rounded or substantially conical, is provided on the inner side of the aperture 12. A plurality of fins or guides 15 may extend vertically on the inner wall of the reduced portion 11 of the casing member to guide the valve member 5 accurately in a vertical direction and to prevent it from shifting from side to side and grooves or channels 13 are provided between the fins to facilitate the flow of liquid. The relation of the valve member 5 and the fins 15 may be observed more particularly in Figs. 1, 2 and 4.

25 The valve member 5 is preferably hollow and, as here shown, comprises a cylindrical member 16 having an enlarged rounded end 17 to seat on the valve seat 14. The upper end is covered by a cap 18 which may be sealed on the hollow cylindrical member by a suitable adhesive or merely by a forced fit. It will be noted that the enlarged end of the valve member and the side of the cap form a snug fit with the fins 15 in the casing member. It has been found that this construction, with the reduced intermediate part, affords excellent operating results in that the effect of the surface tension of the liquid is reduced permitting the valve member 40 to move more freely.

40 In order to seat the valve member securely in position on the valve seat 14 to prevent liquid seeping through, a ball member 6 is provided which is preferably a heavy metal ball, or any other weighted object which is preferably spherical and resistant to alcohol. Various types of metal may be used, for example, Monel metal, stainless steel, tin coated metals, and the like.

45 The baffle member 7, shown more particularly in Figs. 1, 3 and 4, is adapted to be inserted into the upper end of the casing member 2 and to seat an annular shoulder 19 formed on the interior wall of the casing. While the baffle member may be in various forms, the preferred embodiment contemplates a construction with a series of fin members 20 depending downwardly from an upper disc member 21. The lower ends of the fin members 20 seat on the shoulders 19 in the casing member and liquid may pass between the fin members and about the disc member 21. The inner edges 22 of the fin members preferably are bevelled and flared outwardly, as shown at 23, so that they form substantially a conical seat for the ball member 6 when the bottle is inverted. When the bottle is in upright position, the fin members 20 retain the ball on the upper end of the valve so that its full weight is effective in closing the valve. A projection 24 is provided at the apex of the 50 conical seat to prevent the ball from seating too snugly and to cooperate with the bevelled edges 22 of the fins to prevent the ball from being unduly affected by the surface tension of the liquid. The projection 24 always maintains the ball off center so that it is free to roll down-

wardly against the valve as soon as the bottle is tilted sufficiently into upright position.

Referring more particularly to Fig. 4 of the drawings, it will be noted that the angle of the conical seat 23 provided by the inner edges of the fins 22 is such that the ball member 6 will roll upwardly to push the valve back on its seat when the neck of the bottle is tilted downwardly at an angle of substantially forty-five degrees or less. The common way of filling alleged non-refillable bottles is to tilt them at some angle and create a vacuum within the bottle and permit the vacuum to draw the liquid past the valve while the bottle is in inverted position. This is virtually reversing the pouring operation by utilizing the influence of vacuum. The present valve member, being constructed of light material and being hollow, is moved upwardly by the heavy ball when the edges of the fins 22 become tilted very slightly. When the bottle is in inverted position or inverted at an angle greater than forty-five degrees, any tendency for the liquid to run into the bottle creates a pool of liquid about the valve member 5 which floats it into closed position. In addition, the fins 15 cause the liquid to flow along the sides of the valve and impinge against an annular upwardly facing shoulder 25 at the enlarged end of the valve member, which further tends to seat the valve member. 30

The cover 4 is adapted to fit over the upper end of the casing member to further enclose the parts housed therein and to furnish a pouring outlet. The casing member preferably has an outwardly extending flange 26 with a series of 35 projections 27 (Fig. 5) on the outer periphery thereof and the cover 4 preferably has a flared portion undercut on the inside, as shown at 28, so that the projections 27 on the flange of the casing member are adapted to snap into the 40 undercut 28 whereby the casing member and cover are attached to each other. The upper end of the cover member 4 may have a pouring neck 29 provided with a pouring aperture 30 and threaded on its exterior to receive a closure cap 31 and a sealing gasket 32 for sealing the container during shipment. It will be understood, of course, that instead of a closure cap a cork 45 may be inserted into the aperture 30 of the neck portion. 50

The insert, as thus assembled, may be shipped as a unit to bottlers for applying it to containers. The casing member 2 telescopes into the neck of a bottle and the flange 26 and the outer periphery of the cover member 4 rests on the gasket 55 8. Suitable ridges 34 may be provided on the underside of the flange 26 and the cover part 4 adapted to penetrate into the gasket and improve the seal. An annular ring member 9, preferably made of metal with a flange 35 at its 60 upper side, may be dropped over the cover member and the lower edge 10 thereof and bent inwardly under a shoulder 36 on the bottle to lock the parts of the insert in sealed relation on the end of the bottle. Preferably, the ring member 65 9 is made of relatively stiff metal which is not easily removable after application and, if desired, the ring member may have the packers' trade-mark stamped or embossed thereon.

Referring more particularly to Fig. 6 a construction is shown in which the upper end of the insert is substantially flush with the upper end of the container. In this type of construction, the usual screw cap may be utilized for sealing the bottle. The construction of the insert is 70 75

also different in that the casing member and the cover member are joined substantially adjacent to the ball member, whereas in the previous construction the two parts are joined on the rim of the bottle. It will be understood, of course, that in the assembly of the upper and lower housing members, their junction may be at any desired point to facilitate molding and the manufacture thereof. Also, these parts may be locked together by utilizing projections 37 adapted to be snapped into a groove 38. Likewise too, in the construction shown in Fig. 6, a sealing gasket 39, cylindrical in shape, fits about the cylindrical part of the cover member 41. If desired, projections 40 may be formed on the inside of the bottle to prevent the insert from being pulled out of the bottle. Ordinarily, such projections are not necessary because the parts of the inserts are preferably so constructed that any attempt to pull the insert out will break it. It will be noted that in the present construction the pour-out nozzle of cover 41 is connected by a relatively thin annular portion 42 which will break quite readily if an instrument is inserted into the pour-out nozzle to remove the insert.

It will be understood that the parts described herein may be formed of any desired material suitable for the purpose. It has been found that certain types of plastics may be used with excellent advantages in the manufacture of the parts. For example, it has been found that a plastic material such as a phenolic condensation product or a plastic molding material having a vinyl resin base is sufficiently resistant to alcohol and, at the same time, provides an inexpensive construction. This is a property of said materials, not heretofore known. One of the features of the present invention is the construction of the casing member, the valve member, the baffle member, the cover member or any one or more of them of these materials, since they have been found to have distinct advantages over other types of material, such as porcelain and the like. The construction of the valve member of the particular shape and with this material, as noted above, produces excellent results. It will be understood, however, that the invention is not limited to the use of said materials, as it is intended that any other suitable material may be used, if desired.

In the operation of the device, the glass manufacturer furnishes a bottle, and the cap manufacturer or maker of the insert furnishes the insert complete ready to be inserted into the bottle in assembled relation, which minimizes the work of the bottler. Preferably, the band 9 has slight indentations therein adapted to hold the gasket 8 in position therein so that the entire insert, including the band and insert, is shipped as an assembled unit ready to be dropped over the end of the bottle. The bottler places the inserts in the ends of the bottles and runs the bottles through a sealing machine which exerts a pressure downwardly on the upper part of the band and cover parts to form a seal on the rims of the bottles and on the bottoms of the flange and periphery of the casings and covers, respectively, to form a secure seal. While thus compressed, the lower edge 10 of the band is turned inwardly to hold the parts in sealed relation.

The consumer removes the closure 31 and inverts the bottle to pour the contents therefrom. The ball 6 rolls down into its seat and the liquid pressure on the bottom of the valve member forces it off its seat so that the liquid can pass

along the grooves or channel 13 between the fins 15 and through the fins 20 about the side of the baffle 21 and out through the pour-out nozzle 29. As soon as the bottle is returned to its upright position, the valve member is forced back to its seat with a hammer-like blow by the ball 6. It will be noted that substantial space is provided between the bottle and the valve and intermediate the fins 15, as well as about the baffle 1, so that liquid can be readily and freely poured from the bottle. Any attempt to fill the bottle requires the valve 5 to be unseated. This can be done only by inverting the bottle. If the bottle is tipped only to an angle of forty-five degrees with the mouth downward, the ball 6 will retain the valve in closed position. If the bottle is completely inverted or inverted more than forty-five degrees, the lightness of the valve member is such that the liquid will float it into seated position. In addition, the movement of the valve to closed position is aided by the flow of the liquid which impinges against the irregular outside of the valve member as well as the end thereof to force it back into seated position. It has been found that a bottle of this type successfully resists the several known methods of refilling.

It will be seen that the present invention provides an improved nonrefillable bottle which will prevent refilling or tampering with the contents thereof. The several parts are so constructed that they may be readily and inexpensively molded as well as readily and inexpensively assembled. The insert may be sold as a separate unit so that the labor required by the bottler in applying the insert to the bottle is reduced to a minimum. In addition, the cost of the construction has been reduced to a minimum by the simplicity of the construction and the ease of the manufacture and assembly of parts. The parts may be made of plastics having a phenol formaldehyde base, or of plastics having a vinyl resin base, both of which can be made to be sufficiently resistant to alcohol to permit their use in the present construction. By utilizing such material, the cost may be further reduced and the likelihood of sharp particles getting into the contents is eliminated.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a device of the class described, the combination of a casing member having an aperture at its lower end, a plurality of fins on the interior of said casing member directly above said aperture, a substantially cylindrical member rounded at one end adapted to close said aperture and be guided into position over the aperture by said fins, a ball member mounted on the upper end of said valve member, and a baffle above said ball member having a plurality of outwardly flared fins forming a conical seat for said ball member when said casing member is inverted.

2. In a device of the class described, the combination of a casing member having an aperture at its lower end, a plurality of fins on the interior of said casing member directly above said aperture, a substantially cylindrical member rounded at one end adapted to close said aperture and be guided into position over the aperture by said fins, a ball member mounted on the upper

- end of said valve member, a baffle above said ball member having a plurality of outwardly flared fins forming a conical seat for said ball member when said casing member is inverted, and a cover member adapted to be snapped over the upper end of said casing member to hold the parts therein.
3. A baffle member for a nonrefillable bottle having a plurality of fins, the inner edges of said fins forming substantially a conical seat and a projection at the apex of said conical seat extending downwardly intermediate said fin members.
4. In a nonrefillable bottle device adapted to be shipped as a unit and inserted into the neck of a container, the combination of a valve casing member having an upwardly facing shoulder, valve means in said casing, a cover member having a downwardly facing shoulder, said members having cooperating means for locking said members together as a unit, and a baffle member having radially extending portions adapted to be supported by said upwardly facing shoulder and held downwardly by said downwardly facing shoulder.
5. In a nonrefillable bottle device adapted to be assembled and shipped as a unit, the combination of a casing having a flange at its upper end, a plurality of circumferentially spaced projections on said flange, valve means in said casing, and a cover member having an undercut recess snapped over said projections at the upper end of said casing member to attach said members to hold said valve means therein.
6. In a device of the class described, the combination of a casing member formed of a plastic molding material such as a phenolic condensation product, a cover member likewise formed of similar material, and valve means in said casing member, one of said members having a radially extending preformed recess and the other of said members having at least one radially extending preformed projection adapted to be forced into said recess to attach said members together as a unit.
7. In a device of the class described, the combination of a glass container, a casing member extending downwardly into the neck of said container having an aperture at its lower end and a flange at its upper end extending partially over the rim of the container and having locking projections on the outer periphery thereof, valve means in said casing member for closing said aperture, a baffle in said casing member above said valve means, a cover member fitting over said casing member and the end of said container having an annular downwardly depending portion provided with inwardly facing attaching means adapted to interlock with projections on the flange of said casing member to secure said casing and cover members together as a unit, a sealing member beneath said flange extending across the rim of said container and means for permanently securing said cover member to said container.
8. A device adapted to be assembled and shipped as a unit and attached to a bottle or the like to render it nonrefillable, comprising a casing member adapted to extend into the neck of a bottle and having an outwardly extending flange at its upper end and having an upwardly facing shoulder on the interior of the casing adapted to seat a baffle, a baffle member mounted on said shoulder, valve means in said casing member beneath said baffle, said casing flange having outwardly facing attaching means at the peripheral edge thereof, a cover member for said casing member and for the bottle, said cover member having an annular depending portion provided with inwardly facing attaching means adapted to cooperate with said attaching means on the flange of said casing member to detachably secure said casing and cover members together as a unit without reformation of the parts thereof, and an annular sealing gasket at the junction of said outwardly extending flange and said annular depending portion with the upper side of the gasket extending over a portion of the underside of the flange and a portion of the underside of the annular depending portion and the underside of the gasket being adapted to engage the rim of the container to seal both the casing and cover thereto.
9. A nonrefillable bottle comprising in combination, a bottle having a mouth and rim at its upper end; a nonrefillable device adapted to be assembled and shipped as a unit apart from the bottle and adapted to be secured to the bottle to prevent refilling, said nonrefillable device comprising a casing member adapted to extend into the mouth of said bottle and having an outwardly extending flange at its upper end extending over at least a portion of the rim of said bottle, said flange having outwardly facing attaching means at the periphery thereof, a cover member for said casing member and for said bottle, said cover member having an annular depending portion provided with inwardly facing attaching means cooperating with the attaching means on the flange of said casing member to detachably secure said casing and cover members together as a unit without reformation of the parts thereof, and an annular sealing gasket on the rim of said bottle extending under the bottom of the flange of said casing member and the bottom of said depending portion of said cover member at the junction of said flange and depending portion to seal said cover and casing members to the bottle at said junction and to prevent detachment of the casing member from the cover member while secured on said bottle; and means for securing said cover member to said bottle to retain said nonrefillable device in position thereon.
10. In a nonrefillable bottle device adapted to be shipped as a unit and inserted into the neck of a container, the combination of a valve casing member having a flange at its upper end adapted to extend over at least a portion of the rim of a container and having an upwardly facing seat on the interior thereof adapted to seat a baffle, valve means in said casing member, a cover member having a downwardly facing portion adapted to cooperate with said upwardly facing seat on the casing member to secure a baffle member in position, said cover member being mounted on the upper end of said casing member having an annular downwardly projecting portion for encasing said flange, said flange and said projecting portion having cooperating portions for locking said cover and casing members together as a unit, and a baffle member having portions engaged by said upwardly facing seat of the casing member and the baffle engaging surface of said cover member to hold said baffle in position in said device.
